G. A. SMITH.

THROW-OFF DEVICE.

APPLICATION FILED SEPT. 26, 1913.

1,112,727.

Patented Oct. 6, 1914.

UNITED STATES PATENT OFFICE.

GEORGE ANDREWS SMITH, OF SOUTH HILL, VIRGINIA.

THROW-OFF DEVICE.

1,112,727.

Specification of Letters Patent.

Patented Oct. 6, 1914.

Application filed September 26, 1913. Serial No. 792,028.

To all whom it may concern:

Be it known that I, GEORGE A. SMITH, residing at South Hill, in the county of Mecklenburg and State of Virginia, have invented certain new and useful Improvements in Throw-Off Devices, of which the following is a specification.

My present invention has for its object to provide an improved throw off device for use 10 on board assorting machines of the kind disclosed in my co-pending application filed June 14, 1913, Serial No. 773,685. In machines of the present type, the boards of various sizes, are moved along a given path 15 by a conveyer, there being instrumentalities provided at intervals for ejecting the boards of predetermined sizes at predetermined places, and my present invention provides what I consider to be a more practicable and 20 efficient construction of throw off devices than those disclosed in my application above mentioned.

In its general construction, the present invention provides a standard or support, 25 between which and the fence of the machine, the boards are carried by the conveyer. The standard supports an adjustable roller bracket which carries a roller and a vertically yieldable guard therefor. The standard 30 also adjustably supports a shoe to cooperate with the spring finger that is vertically yieldably mounted on an auxiliary standard which is adjustably held by a clamp which is itself adjustably secured to 35 the primary standard, the boards passing between the roller, the guard, and shoe on one side, and the throw off finger on the other side, the parts being so relatively adjusted that boards of a predetermined size 40 will be thrown out by the spring finger after leaving the shoe, while boards of a lesser size will pass beneath the shoe and spring finger without being affected thereby, and boards of greater size will be held from ejection 45 by the guard that is arranged adjacent to the roller.

More subordinately the invention includes those novel details of construction, combination and arrangement of parts, which will 50 all be first fully described, and then be specifically pointed out in the appended claims, reference being had to the accompanying drawing, in which:—

Figure 1 is a perspective view of a portion 55 of a selective assorting machine with my im-

provements applied. Fig. 2 is a detail perspective view of one of the throw off devices. Fig. 3 is a detail section on the line 3—3 of Fig. 1. Figs. 4 and 5 are horizontal sections on the lines 4—4 and 5—5 respectively, of Fig. 3, illustrating the manner in which the throw off finger operates, and Fig. 6 is a view similar to Fig. 5 showing the throw off finger as ejecting a board that has just passed the shoe. Fig. 7 is a detail side elevation of the parts to the left of the line 7—7 in Fig. 3. Fig. 8 is a detail horizontal section on the line 8—8 of Fig. 7.

1 designates the fence of the machine which is mounted on a table 2, that has runways or channels 12 in which the conveyer chains 4 ride, the chains 4 having pushers 5 for engaging the boards B and moving them along edgewise in a continuous longitudinal procession.

10 designates the main or primary standard of the throw off device which is vertically adjustable in a clamp member 11, that is bolted or otherwise secured to the underside of the channel-way 12.

9 is an adjustable bracket clamp mounted on the standard 10 and supporting the auxiliary or secondary standard 14.

The standard 14 carries a block 8 on which the resilient throw off finger 6, is mounted, 85 the block 8 being designed for a limited upward yielding motion by virtue of the slot 7, pin 22, spring 13, and abutment pin 23.

15 designates a roller which is mounted at 16 to the bracket 17, which is adjustably secured at 18, on the standard 10, so as to be susceptible of being located in different horizontal planes.

19 is a guard which is pivoted at 20 to the bracket 17, and is held in position by a stop 21, the guard 19 being susceptible of yielding upwardly when necessary.

25 is the shoe which is adjustably secured at 26 to the standard 10, and the shoe 25 co-operates with the finger 6 to the extent 100 of compressing such finger or moving it out of the path until the board has passed the shoe, whereupon the finger 6 will throw the board over into the receptacle provided for it, as indicated in Figs. 1 and 6 of the drawings.

In operation, the boards are passed along the machine through the throw off devices as indicated in Fig. 1. Boards of a width less than the distance between the chain 4 110

and the underside of the guard 19, and of greater width than the distance between the chain 4 and the underside of the shoe 25, will be engaged by the spring finger 6 as 5 they pass the end 24 of the shoe 25 and be thrown out into the receptacle provided for the purpose, as best indicated in Fig. 1 of the drawings. Boards of other sizes will 10 pass through the particular throw out device and be thrown out by a subsequent throw out device which has been set for the board of the particular size.

From the foregoing description taken in connection with the accompanying drawing, 15 it is thought the complete construction, operation and advantages of the invention will be apparent to those skilled in the art to which it relates.

What I claim is:—

- 20 1. In a board assorting machine, the combination with the conveyer that conveys the boards along and the fence against which the boards lie, of selective throwing out mechanism which comprises a standard, a 25 roller carrying bracket vertically adjustable on said standard, a secondary standard adjustably carried by said primary standard, and a resilient throw out finger carried by said secondary standard, substantially as 30 shown and described.
2. In a throw out device for board assorting machines and the like, a primary standard, a guard member carried by said standard, a secondary standard supported from 35 said primary standard, a resilient throw off finger carried by said secondary standard, and a shoe on said primary standard coöperative with said finger.
3. In a throw out device for board assorting machines and the like, a primary standard, a guard member carried by said standard, a secondary standard supported from 40 said primary standard, a resilient throw off finger carried by said secondary standard, and a shoe on said primary standard coöperative with said finger, means for yieldably supporting said guard member on said standard, and means for yieldably support- 45

ing said throw out finger on said secondary standard.

4. Throw off devices for board assorting machines and the like, comprising a vertical standard, a roller carrying bracket vertically slidably mounted on said standard, means for holding said bracket in position 55 on said standard, a secondary standard, an adjustable clamp bracket connection between said standards for supporting said secondary standard from said primary standard, a resilient throw off finger carried by said secondary standard, a shoe carried by said primary standard to coöperate with said finger and projecting a lesser distance than the projection of said finger, whereby when a board passes between said shoe and finger, 60 said finger will tend to throw off said board when it passes the shoe, and means for restraining the action of said finger if the board be of a greater than the predetermined size for which the throw off mechanism is 65 adjusted to operate.

5. Throw off devices for board assorting machines and the like, comprising a vertical standard, a roller carrying bracket vertically slidably mounted on said standard, means 75 for holding said bracket in position on said standard, a secondary standard, an adjustable clamp bracket connection between said standards for supporting said secondary standard from said primary standard, a resilient throw off finger carried by said secondary standard, a shoe carried by said primary standard to coöperate with said finger and projecting a lesser distance than the projection of said finger, whereby when a 80 board passes between said shoe and finger, said finger will tend to throw off said board when it passes the shoe, and means for restraining the action of said finger if the board be of a greater than the predetermined 85 size for which the throw off mechanism is adjusted to operate.

GEORGE ANDREWS SMITH.
